SWINGING TRAY CONVEYORS
John M. Leach, Port Washington, N.Y.
(P.O. Box 350, Port Jefferson, N.Y.)
Filed July 7, 1961, Ser. No. 122,519
6 Claims. (Cl. 193—110)

The present invention relates to mechanical movements. More particularly, it relates to mechanical movements of the type employed in conveyors such, for example, as pivoted tray or bucket types as described and claimed in co-pending application Serial Number 789,961, now Patent No. 3,031,066, filed Jan. 29, 1959, of which this application is a continuation-in-part.

It is an object of the present invention to provide a mechanical movement which can be used in conveyors and other equipment which is simple in design, dependable in operation and wear resistant even in the presence of adverse operating conditions. The simple design is desirable because equipment such as conveyors is frequently required to fit into small areas which necessitates compact components. The more compact the design the more inaccessible the component which gives rise to the need for dependable operation, and, because conveyors frequently handle dusty and abrasive materials, it is necessary that mechanical movements be free from complicated elements which are always vulnerable to wear.

It is another object of the present invention to provide a mechanical movement in which some of the elements can be made to move at a much higher rate than other of the elements.

It is a further object of the present invention to provide a mechanical movement in which certain elements can be made to move at a rate which is completely independent of the rate of movement of the other elements.

Other objects and advantages of the present invention will become apparent to those skilled in the art from consideration of the following description of what are now considered to be the preferred physical embodiments of the invention.

In the accompanying drawings in which the same reference characters refer to the same elements throughout;

FIG. 1 is a fragmentary sectional view of a conveyor showing one form of mechanical movement of the present invention;

FIG. 2 is a similar view showing another form of the present invention;

FIG. 3 is a plan view of a section of a chain element of the present invention;

FIG. 4 is a view similar to FIG. 1 but showing another form of mechanical movement of the present invention;

FIG. 5 shows an electrical wiring diagram of the type used to control the mechanical movement shown in FIG. 4;

FIG. 6 is a view similar to FIG. 1 but showing another form of the mechanical movement of the present invention;

FIG. 7 is a fragmentary detailed view of certain elements appearing in FIG. 6 but viewed from above, and

FIG. 8 is a fragmentary detailed view of the same elements of FIG. 7 but viewed from the side.

For the purpose of explanation the present invention has been disclosed as embodied in the same type of conveying equipment as that disclosed in the above identified parent application and it is to be understood that all of the disclosure of that application is applicable here with the exception of the mechanical movement for causing the chain links to fold together which is replaced here by the mechanical movements of the pres-

2

ent invention. The present disclosure has been restricted to the mechanical movements, per se, to avoid duplication of explanatory matter.

The mechanical movement of the present invention includes a chain which is shown in FIG. 1, for example, as comprising outside links 10 which are pivotally connected to inside links 12 by pins 13 which may be in the form of hollow thimbles. If desired, the chain may also include rollers 14 which are journaled on the pins 13.

The chain is supported by and moves along a support or track 16 under the moving action of any suitable prime mover such as the sprocket drive shown in the parent application. A suitable top surface 18 provides protection to the chain and also restricts movement of the chain links to the direction of the lengthwise movement of the entire chain. At a selected point in the travel of the chain, the surface 18 deflects away from the other surface 16 to provide an expanded area between the surfaces as shown at 20.

Every other one of the pins or thimbles is provided with a side extension 24 which is preferably in the form of a roller suitably journaled in any desired manner in the thimble 13.

25 A cam 26 is suitably attached to some part of the supporting structure, for example to one side of the surface member 16. The cam 26 is positioned in the path of the side extensions 24 and has a steep slope so that lengthwise movement of the chain brings the side extensions 24 one after the other into contact with the cam and its steep slope causes the pivotal connection of the chain at the moment in contact with the cam 26 to be moved rapidly in a direction at right angles to the direction of movement of the chain. The faster this movement of the pivotal connection at right angles takes place the quicker the side-moving pivotal connection will get off of dead-center and the less the force required to be exerted by the chain pushing in the direction shown by the arrow in FIG. 1. The steepness of the slope of the cam 26 causes this side movement of the pivotal connection to be at a much higher rate than the lengthwise movement of the chain. This is made possible in the mechanical movement of the present invention only because the links ahead of those undergoing folding action and which have already been moved into maximum folded position can undergo slight retrograde movement and thus give the slack necessary for the pivotal connection undergoing side movement to move at a higher rate than the lengthwise movement of the chain.

50 The extent which it is desirable for the cam 26 to move the pivotal connections sidewise and at right angles to the direction of lengthwise movement of the chain to get the connection off of dead-center so that further folding action will require very little force exerted by the chain will vary with the pitch of the chain. For example, a three inch pitch chain requires that the links be moved until their longitudinal center lines form approximately a twenty-five degree angle with the center line of the chain which is moving lengthwise with the links not folded.

55 This rapid sidewise movement of the pivotal connections greatly reduces the load time on the pivotal connections during sidewise movement and thus greatly reduces wear on the parts and increases their operating life.

60 In order to stop the folding action on the part of the links at the most desirable point a surface in the form of a plate 22 is suitably attached to the inside link 12 of each pair of links which contacts a side surface 11 of the outside link 10 of the same pair and thus provides a positive stop.

FIG. 3 shows a section of chain which forms an element of the present invention in which the shapes of the links themselves provide cooperating stop surfaces. The links 49 are shaped as shown and are pivotally connected by pins 41 and every other pin 41 is provided with a side extension 46 which may be the same as side extensions 24 of FIG. 1.

The function of the chain shown in FIG. 3 is the same as that shown in FIG. 1 except the folding action of the links is stopped when surfaces 48 on one set of links contacts surfaces 50 on the next pair of links.

In the modification of the present invention shown in FIG. 2, the side extensions and cam 24 are omitted and instead a projection is formed on the surface 16 which is preferably in the form of a roller 30 suitably journaled on stud 32. A projection 21 is also preferably suitably attached to the top member 20.

In the operation of this mechanical movement, as the chain moves lengthwise each pivotal connection which does not move sidewise at right angles to the direction of movement of the chain lengthwise, is caused to roll up and over the roller 30. Just as the pivotal connection starts down from the highest part of roller 30, the roller 14 of the link 12 immediately preceding this pivotal connection contacts the surface 21 which drives this pivotal connection down into the position shown at 34 in FIG. 2. This causes the link 10 immediately following to fulcrum on the top of the roller 30 and thus move the immediately following pivotal connection very rapidly into the position shown at 36 in FIG. 2 at which point that particular pivotal connection is off of its dead-center. During the fulcruming action of the link 10 the completely folded links will here again undergo some retrograde action in order to provide the slack necessary for the side moving pivotal connection to move at a higher rate than the movement of the chain lengthwise and thus reduce wear on the pivotal connections.

In the modification shown in FIG. 4 the facility for moving the pivotal connections sidewise and at right angles to the direction of lengthwise movement of the chain, comprises an axially movable member 60 which can be suitably supported and guided for movement by fixed collars 61 and 62. The member 60 is carried by an arm 63 which is suitably connected to the armature of an electrical solenoid 64 which in FIG. 4 is shown in the fully retracted position at which point the member 60 has moved the particular pivotal connection undergoing side movement off of its dead-center.

The energization of solenoid 64 is effected when a pivotal connection 38 immediately preceding the pivotal connection to be moved sidewise contacts a suitable limit switch LS1. Referring to the circuit shown in FIG. 5, this causes the normally open limit switch LS1 to close which completes a circuit from line L1 through the normally closed contacts of relay R1 to line L2 through the solenoid 64 which causes the axially movable member 60 to move the pivotal connection as above explained.

When the member 60 reaches its maximum movement, a cam 65 carried by member 60 activates limit switch LS2 which causes a circuit to be completed from line L1, through limit switch LS1, through limit switch LS2, and through relay R1 to line L2. This causes relay R1 to function so as to open its normally closed contacts NC and close its normally open contacts NO. This instantly breaks the circuit through solenoid 64 which immediately causes member 60 to lower rapidly under its own weight. The fact that pivotal connection 38 may still be resting on limit switch LS1 does not reactivate solenoid 64 again because relay R1 has established a holding circuit for itself through its contacts NO which remain closed until pivotal connection 38 does leave limit switch LS1 at which time relay R1 deactivates and the system remains inactive until the next non-sidewise moving pivotal connection contacts limit switch LS1.

In the modification shown in FIGS. 4 and 5, the wear-

saving rapid folding action can be accomplished at a very high rate because the rate of movement of the member 60 is not at all limited by the rate of lengthwise movement of the chain. Here again the folded links undergo slight retrograde action to permit the rapid folding action to take place. The independent movement of member 60 also insures that regardless of how rapid may be its upward movement, its downward movement will be sufficiently rapid to prevent it from interfering with the immediately following pivotal connection.

When two chains are operating simultaneously as shown in the parent application, two solenoids will be required, one for each chain, so that a second solenoid 66 is shown in the circuit of FIG. 5 which would be controlled by the same electrical media and simultaneously with solenoid 64. It is, of course, possible to control all of the solenoids for several load points on the same conveyor by just one set of controls as shown in FIG. 5.

In the modification shown in FIGS. 6, 7 and 8, an axially movable member 68 is guided for movement in collars 70 and 72 and carries a pin projection 74 which is contacted so as to move member 68 upwardly and thus move the pivotal connection at right angles to the lengthwise movement of the chain by an extension 84-86 carried by a lever 76 as shown in FIG. 7. The lever 76 is suitably pivoted at 78 and carries an extension 80 which is in position to be contacted by a pivoted connection 39 as shown in FIG. 6.

The side extension 84-86 comprises a section 84 which is suitably affixed to the lever 76 and is suitably articulated to a swingable section 86 by a pivot 91. An extension arm 92 on the swingable section 86 prevents the latter from swinging downwardly as viewed in FIG. 8 but allows section 86 to swing upwardly freely.

In the operation of the modification just described, as the pivotal connection 39 moves on to the lever extension 80, the lever 76 is rotated clockwise as viewed in FIG. 6 and the section 86 bears upwardly on the pin 74 which moves axially movable member 68 upwardly to move the pivotal connection at right angles the same as in the preceding modifications. Just as the member 68 reaches its highest point, the edge 90 of the swingable section 86 rides out from under the pin 74 as shown in FIG. 6 which allows the member 68 to drop rapidly downwardly under its own weight, which action is just starting as shown in FIG. 6. When the pivotal connection 39 moves off of the lever extension 80, the lever 76 will rotate counterclockwise and when the swingable section 86 strikes the pin 74, the section 86 will swing counterclockwise and slide under the pin 74 again as shown in FIG. 7, at which point the mechanical movement will be in readiness for another cycle. The operation of the modification of FIG. 6 is otherwise the same as in the previous modifications.

It will be noted that the mechanical movements of the present invention are all simple in design and require a minimum of movable parts, occupy a small space, and accomplish their functions with a minimum of force and effort. All of these factors contribute to reduced wear and long life on the part of the mechanism.

It is to be understood that the forms of this invention described herein represent only the preferred embodiments of the present invention since many changes can be made in these embodiments without departing from the spirit of the invention.

The invention having been described, what is claimed is:

1. A conveyor comprising a chain having links and pivotal connections between the links, means for moving the chain lengthwise, a guide for the chain having opposite surfaces to retain the chain in substantially straight line position during movement, one surface of the guide deflecting sharply away from the other surface at a selected point in the movement of the chain to provide a sharply expanded area between the guide surfaces, means for moving a pivotal connection at right angles to the

direction of movement of the chain into the sharply expanded area and at a higher rate of movement than the rate of movement of the chain lengthwise, and means on one link adjacent the so moved pivotal connection which contacts the other link at a point near the so moved pivotal connection to limit the movement of the two links away from the line of movement of the chain lengthwise.

2. A mechanical movement comprising a chain having links and pivotal connections between the links, means for moving the chain lengthwise, a guide for the chain having opposite surfaces to retain the chain in substantially straight line position during movement, one surface of the guide deflecting sharply away from the other surface at a selected point in the movement of the chain to provide a sharply expanded area between the guide surfaces, means for moving a pivotal connection at right angles to the direction of movement of the chain into the sharply expanded area and at a higher rate of movement than the rate of movement of the chain lengthwise so as to cause retrograde movement of the pivotal connection immediately preceding the pivotal connection so moved at right angles to the direction of movement of the chain lengthwise, and means for limiting the extent of right angular movement of the pivotal connection.

3. A mechanical movement comprising a chain having links and pivotal connections between the links, means for moving the chain lengthwise, a guide for the chain having opposite surfaces to retain the chain in substantially straight line position during movement, one surface of the guide deflecting sharply away from the other surface at a selected point in the movement of the chain to provide a sharply expanded area between the guide surfaces, and means for moving a pivotal connection at right angles to the direction of movement of the chain into the sharply expanded area and at a higher rate of movement than the rate of movement of the chain lengthwise.

4. A mechanical movement comprising a chain having links and pivotal connections between the links, means for moving the chain lengthwise, a guide for the chain having opposite surfaces to retain the chain in substantially straight line position during movement, one surface of the guide deflecting sharply away from the other surface at a selected point in the movement of the chain to provide a sharply expanded area between the guide surfaces, side extensions attached to some of the pivotal connections, means for engaging the side extensions to move the attached pivotal connections at right angles to the direction of movement of the chain into the sharply expanded area

and at a higher rate of movement than the rate of movement of the chain lengthwise.

5. A mechanical movement comprising a chain having links and pivotal connections between the links, means for moving the chain lengthwise, means for moving every other pivotal connection in a direction at right angles to the direction of movement of the chain lengthwise comprising a surface over which the chain moves, a projection extending from the surface over which each pivotal connection which does not so move at right angles to the direction of movement of the chain lengthwise moves up and over, a second surface positioned so that as a pivotal connection moves over the said projection the pivotal connection immediately preceding contacts the said second named surface which causes the link immediately following the pivotal connection moving over the projection to be fulcrumed on the projection and thereby move the pivotal connection immediately following said last named link at right angles to the direction of movement of the chain lengthwise.

6. A mechanical movement comprising a chain having links and pivotal connections between the links, means for moving the chain lengthwise, a guide for the chain having opposite surfaces to retain the chain in substantially straight line position during movement, one surface of the guide deflecting sharply away from the other surface at a selected point in the movement of the chain to provide a sharply expanded area between the guide surfaces, means for moving at least one of the pivotal connections at right angles to the direction of movement of the chain lengthwise into the sharply expanded area and at a higher rate of movement than the rate of movement of the chain lengthwise comprising an axially movable member, means for guiding the member so that it will contact the pivotal connection to be moved at right angles to the direction of movement of the chain, and means for moving the axially movable member to so move the pivotal connection at right angles to the direction of movement of the chain and at a higher rate and then retract so that it does not interfere with the movement of the immediately following pivotal connection.
